FIREARM

Alex Seidel, Oberndorf-on-the-Neckar, Germany,
assignor to Mauser-Werke A.-G., Oberndorf-
on-the-Neckar, Germany, a joint-stock com-
pany of Germany

Original application August 20, 1935, Serial No.
37,078. Divided and this application August
24, 1937, Serial No. 160,680. In Germany May
6, 1935

6 Claims. (Cl. 42—1)

This invention relates to firearms, and particularly to automatic pistols with hammer and trigger.

It is an object of the invention to provide an improved magazine holder which, as known per se, cooperates with the push rod for the hammer. To this effect the push rod, the hammer spring and the magazine holder are combined into a unit, the insertion and removal of which are thus simplified, and the unit cannot be placed in a wrong position.

A further object of the invention is to provide a device for holding the magazine for pistols, whose shape is adapted to the shape of the pistol, and does not expose any openings in its active and inactive positions, and further notwithstanding all the foregoing is simple, safe and easily manipulated.

The invention will now be more fully described in connection with the drawing of which,

Fig. 1 is a longitudinal section of the rearmost part of a pistol stock with the magazine holder, the hammer spring and the hammer,

Fig. 2 is an elevation showing the magazine holder with the push rod and the hammer spring disassembled,

Fig. 3 is a section on the line A—B of Fig. 2, and

Fig. 4 is a section on the line C—D of Fig. 3. 151 is the magazine holder which is placed in the stock 1 of the pistol and supports the magazine 85. 158 is the push rod, 126 is the hammer spring on the push rod, and 159 is the head of the push rod with which the hammer is connected as indicated in Fig. 1. The lower end of the push rod 158 has lateral projections 150 which are introduced through notches in the holder when it is desired to connect the parts of the unit. It will be understood that the projections 150 are not in active position when the unit is inserted in the pistol, and the spring 126 is compressed, as shown in Fig. 1. Relative rotation of the parts is prevented in this position by an edge 156 of the magazine 85 which engages in a seat of the magazine holder 151. When the unit is removed, the spring 126 expands, and the projections 150 hold the push rod 158 against turning, by engaging in notches 154 at the top of the central cavity 153 of the holder, and against abutments 155 formed by such notches, so that the push rod is not forced off by its spring 126.

To extract the unit, the side wall of the pistol stock is removed, the holder is disengaged from the edge 156 of the magazine, and the push rod, the hammer spring and the holder are extracted

together. For detaching the rod 158 from the holder 151, the rod 158 is pushed down into the central cavity of the holder 151 against the reaction of the hammer spring 126, until the projections 150 have passed the notches 154 in the holder. The rod is now turned through 90°, and extracted upwardly while the spring 126 expands.

By making the bayonet joint one-sided, for instance, by making its two projections 150 of different size, the parts of the unit will fit only in one definite position with respect to each other. Since they are held against relative rotation when assembled, the unit will always fit in the proper position.

The push rod 158 and its head 159, and the projections 150, are preferably forged in one piece, so that the manufacture thereof is facilitated and cheapened.

Furthermore the magazine holder 151 has a notched lug 176 which bears on an edge 177 at the upper end of the edge member 156 which, as described, is secured to the magazine 85. The spring 126 which is under initial tension, bears on the top 176 of the magazine holder 151 and turns the holder about its edge bearing 176, 177 until a lug 181 at the lower end of the holder engages in a recess 182 in the magazine wall. The leverage at which the strong hammer spring 126 acts, is large compared with the leverage of the magazine 85 at the lug 181, and therefore the magazine is firmly forced into the stock, and held in position.

The lower face of the magazine holder 151 is grooved at 185. To extract the magazine 85, pressure in an inwardly inclined direction is exerted against the holder by its grooves. The holder 151 rocks about its edge bearing 176, 177 and the lug 181 is extracted from the notch 182 of the magazine whereupon the magazine can be fully extracted. The rocking movement of the holder 151 is limited by an abutment 187 in the stock 1 so that the holder will not jump from its edge bearing 176, 177.

An important advantage of the magazine holder 151 according to my invention is that it closes the recess in which it is positioned, when the magazine 85 is inserted, and when it is extracted, so that access of dirt to the recess, to the cock spring 126, and to the push rod 158 is prevented. This is effected by the lug 181 at one side of the holder engaging in the recess 182 of the magazine bottom at one side of the holder, and a strip 193 at its other side, which co-operates with a guard 191 of the stock. The lower end of the magazine holder is flush with the bottom 55

of the magazine and the under side of the stock and thus does not interfere with the manipulation of the pistol, as in the old pistols.

The present application is a division of application's co-pending application, Serial No. 37,078, filed August 20, 1935.

What I claim is:

1. In a firearm having a magazine, a stock and a hammer; an operating rod for the hammer, said rod being enclosed in a cavity in the stock, a magazine lock in the base of the cavity for retaining a magazine in the stock, a bayonet joint connection between the magazine lock and the hammer operating rod, and means for removably securing the magazine lock in the stock.
- 10 2. In a firearm according to claim 1, in which two different lugs are provided on the operating rod for the bayonet joint to enable the rod to be assembled with the magazine lock in one position only.
- 15 3. In a firearm having a magazine, a stock and a hammer; an operating rod for the hammer, said rod being enclosed in a cavity in the stock, a magazine lock in the base of the cavity for retaining a magazine in the stock, a bayonet joint connection between the magazine lock and the hammer operating rod, means for removably securing the magazine lock in the stock, a hammer operating spring abutting between the rod and the magazine lock, said spring biasing the

lock into magazine retaining position, and a bearing in the cavity of the stock for securing the magazine lock in the stock with freedom to tilt about said bearing to retain and release the magazine.

4. In a firearm according to claim 3, in which the spring acts on the magazine lock with a greater leverage than that of the magazine about the bearing axis.

5. In a firearm having a magazine, a stock, and a hammer; an operating rod for the hammer, said rod being enclosed in a cavity in the stock, a magazine lock in the base of the cavity for retaining a magazine in the stock, a bayonet joint connection between the magazine lock and the hammer operating rod, means for removably securing the magazine lock in the stock, a hammer operating spring abutting between the rod and the magazine lock, said spring biasing the lock into magazine retaining position, and a 20 knife edge bearing in the cavity of the stock for securing the magazine lock in the stock with freedom to tilt about said knife edge bearing to retain and release the magazine.

6. In a firearm according to claim 3, in which the magazine lock closes the bottom of the cavity and is flush with the adjacent external surface of the stock.

ALEX SEIDEL.
